UNITED STATES PATENT OFFICE.

WILLIAM W. LASKER, OF BROOKLYN, NEW YORK, ASSIGNOR, BY MESNE ASSIGNMENTS, TO REMINGTON RAND INC., OF NEW YORK, N. Y., A CORPORATION OF DELAWARE.

ACTUATING-BAR CONTROL FOR ACCOUNTING MACHINES.

Application filed November 14, 1918, Serial No. 262,526. Renewed March 21, 1925.

This invention relates to improvements in printing accounting machines, these improvements being applied to accounting machines having registering and printing elements comprising type sectors and reciprocating rack bars positively driven for operating the type sectors. Such a machine is described in detail in my copending application Serial No. 158,142, filed March 28th, 1917; and, therefore, only the parts of such machine are herein described as are necessary for an understanding of the new improvements.

In said machine the type are mounted upon arcuate sections of the type sectors and are driven by intermeshing rack bars. As the type upon said sectors render one side of the sector heavier than the other, there is a tendency of the type sector and the associated rack bar, to move in a retrograde direction after they have been moved forwardly to printing position. One object of the present invention is to provide improved and efficient means for preventing this result, when items are printed and also when totals are printed.

In said machine, each of the rack bars is provided with a depressible abutment lever provided with an abutment against which, when the abutment is raised, there engages a transverse reciprocating drive bar for positively driving the rack bars and the type sectors to item printing or total taking position, the accumulating wheels which mesh with the type sectors being provided with projections adapted to engage a part for depressing said abutment levers for disengaging them from said transverse bar when total taking position is reached. Another improvement herein, has for its object to provide an improved arrangement for accomplishing this last named result.

In said machine, an accumulator and a carrying mechanism are provided in which settable levers are set by the accumulator when carrying is to be effected. These settable levers are adapted, when set, to lower, into operative position, carrying bars adapted to engage and kick back the rack bar of the next higher order so that an additional space is registered on the associated accumulator. When this operation takes place it is desirable to avoid the possibility that any but the desired rack bar be kicked

back. Therefore, another object of the invention is to provide means which will prevent the accidental moving back of the rack bar except when carrying is to be effected thereby.

After the above desired carrying has been effected it is necessary to restore the rack bars to their normal position; and another object of the invention is to provide a convenient and efficient means for effecting this restoring.

Another object of the invention is to provide means for positively restoring the abutment levers to depressed position after they have been raised to driving engagement with the drive bar.

Another object of the invention is to provide a fixed zero stop for holding the rack bars in zero position until they are lifted therefrom for the registering of a numeral.

Another object is to provide means for locking any individual abutment lever depressed so that it will not be driven forward by the drive bar. This locking has for its object to accomplish the well-known "splitting" of the accounting mechanism into separate columns.

These and other objects will appear as the description proceeds; and while herein I have described minute details of the invention, the invention is not limited to these, since the details of construction and combination may be greatly varied without departing from the spirit and scope of the invention as claimed.

In the accompanying drawings showing by way of example one of the many possible embodiments of the invention,—

Fig. 1 is a longitudinal vertical sectional view through the printing and accounting machine, showing in side elevation the parts necessary for a proper understanding of the present invention;

Fig. 2 is a side elevation of the various mechanisms for controlling the rack bars and type sectors;

Fig. 3 is a perspective view of the pawl-carrying frame carrying pawls for preventing retrograde movement of the rack bars during the total taking process;

Fig. 4 is an outside elevation of said frame;

Fig. 5 is a fragmental inside elevation, partly in vertical section, showing the means

for operating the depressing device for depressing the abutment levers during total taking;

Fig. 6 is a side elevation of depressing devices;

Fig. 7 is an edge elevation of the same;

Fig. 8 is a longitudinal sectional view showing the means for locking the abutment lever in operating position;

Fig. 9 is a side elevation showing the mechanism for operating the total taking lever for initiating the total taking operation; and

Fig. 10 is a plan of the total taking lever.

Fig. 11 is a detail perspective view of the rack bar and abutment bar actuating mechanism in normal position.

Fig. 12 is a side elevation of Fig. 11 showing in full lines a position just before the trip lever engages a stop pin and in dotted lines a position after engagement.

Fig. 13 is a detail elevational view of the carrying mechanism showing in full lines a position just before carrying is effected and in dotted lines mechanism actuated when carrying takes place.

Fig. 14 is a detail plan view of Fig. 13.

Fig. 15 is a detail elevational view of the total taking mechanism with members in position to take the total on the forward stroke of the drive bar.

In the said copending application, means are shown for feeding perforated cards to an analyzer comprising a reciprocating pin box provided with pins adapted to feel the cards and on finding perforations therein, to pass therethrough to raise registering stop pins corresponding to the perforations corresponding to numerals, the naught stop being normally raised and adapted by suitable connections to be depressed by the raising of the numeral stop pins.

In the present specification, the left hand end of the machine, as shown in Fig. 1, is considered the forward end of the machine.

Referring more particularly to the drawings of the present specification, there is shown the cheek plates 10, between which cheek plates various mechanisms of one unit 50 of the accounting machine are mounted, these cheek plates being carried on a suitable base or frame not shown. Between said cheek plates there are mounted a plurality of rows of numeral stop pins 11 vertically slidable in upper guide plates 12 and lower guide plates 13 carried upon cross plates 14 mounted upon the cheek plates.

The rack bars and positioning mechanism.

Slidably disposed above each row of pins 11 is a reciprocating rack bar 20 guided in a comb plate 21, and on a rod 22 mounted in the cheek plates and received in a slot 24 in the rear part of the rack bar. On the lower

plurality of ratchet teeth 25 comprising rearwardly facing ratchet shoulders used for the purpose of preventing the return of rack bars 20 when taking a total, as will be described in detail later.

The forward part of the upper edge of each rack bar 20 is provided with a series of teeth 28 adapted to mesh with a gear wheel 29 fixed upon the side of each type sector 30 rotatably mounted upon the sector or register shaft 31. Each sector is provided with a series of printing type 32 and a series of gear teeth 33 adapted to engage with the accumulator wheels 34 (Fig. 5).

Against one side of each rack bar 20 there is disposed an abutment lever 40 pivoted at its forward end to the rack bar and extending rearwardly along said rack bar above said rod 22. In Figs. 1 and 11 the abutment lever 40 is shown in depressed position, while in Fig. 12 it is in raised position.

The intermediate part of the abutment lever 40 is slightly laterally offset forming a space for the reception of a tripping elbow lever 44 pivotally fulcrumed at its elbow part to the side of the rack bar 20 and provided at its forward end with a lateral projecting pin 45 engaging in a small longitudinal slot 46 in the abutment lever. The lower end of the elbow lever is provided with a laterally turned end forming an inclined face 48 and a forward shoulder 49.

The rack bar 20 is provided with an upstanding abutment provided with an inwardly disposed shoulder 50, which when the abutment lever is raised, is opposed to and slightly spaced from the outwardly disposed shoulder 51, formed by an upstanding abutment on the abutment lever. Between said shoulders is disposed a reciprocating rack bar 52 which is reciprocated forward and backward by suitable means controlled by a suitable cam control means, as explained in said copending application.

When the transverse bar 52 is retracted, it engages the shoulder 50 and retracts the rack bars, the abutment levers and the elbow levers, whereupon said inclined face 53 of the abutment lever engages the fixed zero stop 54 and permits the shoulder 55 to engage the outer face of the zero stop.

When the transverse drive bar 52 commences its forward movement, if no numeral stop 11 associated with any rack bar and associated abutment lever is raised, the shoulder 51 remains depressed and the drive bar passes on without moving the rack bar. If, however, in accordance with the perforations of the card being analyzed, one of the 125 numeral stop pins 11 has been raised, the lower edge 56 of the abutment lever 40 is engaged by the stop pin and the shoulder 55 disengaged from the zero stop. This takes place before the drive bar 52 com-

5 mences its forward movement. The raising of an abutment lever 40 brings the shoulder 51 in front of the drive bar 52 which drives the rack bar 20 and said abutment lever 5 forward on its forward movement until the shoulder 49 comes into contact with the raised stop pin 11, whereupon the elbow lever is rocked, thus depressing the abutment lever and freeing the transverse bar 52 which 10 passes on to complete its cycle of movement. This action is clearly shown in Fig. 12, the dot and dash lines indicating the position of the abutment bar after it is depressed.

15 15 This forward movement of a rack bar 20 rocks the type sector 30 and brings the type 32 corresponding to the raised stop pin in front of the reciprocating printing carriage described in said copending application, 20 whereup the printing carriage is moved toward the type and presses the paper carried thereon against the type and prints the number corresponding to the raised pin.

25 As is obvious by an inspection of Fig. 1, the part of the type sector carrying the type is more remote from the center of the type sector than the other parts thereof; the weight of this part tends after the transverse bar 52 has been freed, to cause the type segment to assume a movement which is anti-clockwise in the said Fig. 1. During the registering of items, this anti-clockwise movement is prevented by the engagement of the outwardly and downwardly facing shoulder 57 with the raised stop pin 11 when the abutment lever is depressed as above noted. This is shown in dot and dash position in Fig. 12.

40 The accumulating mechanism or accumulator is carried in an accumulator carriage 65 disposed between the cheek plates 10.

These need be only briefly mentioned since they are fully described in said copending application.

45 *The accumulator carriage.*

50 The accumulator carriage 65 comprises a pair of spaced side plates 66 (Figs. 1, 13 and 14), each provided with a guide slot 67 at its lower rearward end and an upper slot 68 at its upper forward end. A releasing rod 70 fixed between said cheek plates and received in said lower guide slots, and a fixed fulcrum rod 71 received in said upper guide slot, guide the accumulator carriage in its reciprocating movement. In addition to the above, further guiding means is afforded by the accumulator shaft 73 fixed between the lower part of said spaced side plates and adjacent to the gear teeth of the accumulator wheels 34 and projecting beyond the cheek plates. The outer ends of said accumulator shaft are engaged and reciprocated by a suitable reciprocating mechanism which, at the proper time, brings accumulator wheels 34

5 into and out of engagement with the gear teeth 33 described in copending application Serial No. 158,142 filed March 28, 1917.

70 *The accumulator.*

75 Upon the accumulator shaft 73 there are disposed a plurality of shouldered bushings 77 (Fig. 5) on which are disposed the accumulator gear wheels 34 each provided with ten teeth adapted to mesh with the gear teeth of the type sector. Each accumulator wheel carries a projecting pin 80 on which is rotatably mounted a rotating roller or roller projection 81. Secured to each accumulator wheel is a collar 79 provided with a triangular projection 82 providing a radial face 83 (Fig. 1) and an inclined forward face 84, the object of which will be explained.

80 85 *The transfer or carrying mechanism.*

90 Between the side plates of the accumulator carriage is carried the transfer or carry-over mechanism of the accumulator for moving each accumulator wheel one tooth space when the accumulator wheel of the next lower order has moved ten-tooth-spaces or one complete revolution. This mechanism comprises a plurality of settable levers 87, intermediately fulcrumed on the fulcrum rod 88 mounted between the said plates of the carriage. Each settable lever is provided with an end 89 adapted to engage the radial face 83 of its accumulator wheel and to be engaged and lifted by the inclined face 84 when the projection 82 makes a complete revolution as shown in Fig. 13. At the rearward end of the accumulator carriage is disposed the detent rod 90 on which are fulcrumed the detents 91 having forward 100 projecting upper ends 92 adapted to engage over the rearward ends of the settable levers 87 when the accumulator carriage is in its forward position, and when the corresponding settable levers are rocked by the raising of the end 89. The lower arms 93 of the detent levers are adapted to engage the guide rod 70 when the accumulator carriage is reciprocated rearwardly, whereupon the detent levers are moved to the position of 110 Fig. 1 against the action of the springs 96 strained between the detent lever and the hooks 98 carried by the comb plate 99, between the teeth of which are held in spaced relation the settable levers 87 and the detent levers 91. When this releasing takes place the forward ends of the settable levers 87 are drawn down by means of the spring 101 strained between the forward end of each settable lever 87 of the hook plate 102 120 mounted between the side plates of the carriage.

125 Fulcrumed to the inner face of each of the respective side plates is a restoring lever 104, fulcrumed at 105, and provided at one end 130

with a lower cam face 106 adapted to be engaged by the restoring rod 107, mounted between the cheek plates 10, for raising the restoring levers when the accumulator carriage is retracted rearwardly. Between the restoring levers 104 is carried a supporting rod 109 from which hang the pendant links 110 provided with slots 111 receiving said supporting rod. The upper portion of these pendant links are also provided with laterally turned lips 112 adapted to engage over the associated settable levers and to hold the pendant links in raised position when the settable levers are in the position of Fig. 1, but to permit the pendant links to be drawn down under the action of the springs 114, when the end 89 of the settable levers are raised by the cam face 84. To the lower end of each pendant link 110 is pivotally connected the rearward end of a carrying bar 116, the forward end of which bar is pivotally connected to the lower end of the carrying lever 117 yieldably held forward by means of a spring 118 strained between the hook 119 of the carrying lever and the hook plate 120 carried between the side plates of the carriage. A spring 121 strained between said hook plate 120 and a hook 122 on the rear end of the restoring levers 104 yieldably holds the rear ends of the restoring levers in depressed position. The comb plate 123 holds the rear part of the carrying bars 116 in spaced relation. The outer end 125 of each carrying lever is provided with a cam engaging roller 126 adapted to be engaged by one of the stepped cams 127 of the carrying cam plate 128, supported on rollers 129 engaging in the guide slots 130 in the cheek plates 10.

This cam plate 128 is reciprocated forwardly after the items set up by the type sectors have been transferred to the accumulator wheels. When the carrying bar 116 is raised as in Fig. 1, it does not come in contact with the inwardly turned shoulder 50 of the reciprocating rack bars, but when the settable levers are rocked and the pendant links and the rear end of the carrying bar 116 lowered, the carrying bar is in position to engage the shoulder 50, when the lower part of the carrying lever 117 is rocked backward through the action of the cams 127 shown in dotted lines in Fig. 13.

The carrying cam reciprocating mechanism.

For reciprocating the cam plate 128 there are provided a pair of reciprocating racks 131, one on each side of the accounting machine unit, secured at their inner ends to the cam plate and provided at the lower edge with rack teeth 132 adapted to be engaged by the pinion 133 supported upon a pinion spindle 134 passing through both pinion slots 135 in the cheek plates 10. Beneath each pinion and meshing therewith is

a fixed rack 137 secured to the outer face of the cheek plate. Fulcrumed as at 138 to the outer face of each cheek plate is a spindle drive lever 139 provided with an upper end slot 140 receiving the spindle 134.

Suitable means, described in said copending application, are provided for reciprocating said levers 139 to cause said cam plate to be reciprocated forwardly when carrying is to be effected.

The lower end of each detent lever 91 (Figs. 1 and 13) is provided with an outwardly projecting tail 150 having a laterally turned end 151 adapted to engage behind a lug 152 on the upper edge of the rack bar 20 of the next higher order. When a settable lever 87 is not set as when no carrying from its accumulator wheel is to be effected, the detent lever 91 remains in the position of Fig. 1, and the laterally turned end 151 prevents the accidental rearward movement of the rack bar.

The carrying operation.

Considering the accumulator wheels to be in zero position as shown in Fig. 1, any item that is set up by the type sectors rotates the associated accumulator wheel in a direction which is clockwise of Fig. 1, when the type sectors are returning to their initial position.

As there will be no individual digit greater than 9, there will be no complete revolution of the accumulator wheel when the first item is set up. If there should be an additional item set up which added to the previous item gives a number greater than 10, the accumulator wheel will rotate more than one revolution and in so doing, the cam face 84 will engage the end 89 as shown in Fig. 13 and rock the associated settable lever 100 causing a lowering of the associated pendant lever 110 and the associated carrying bar 116, in turn associated with the shoulder 50 of the rack bar of the type sector and accumulator wheel of the next higher order. 110 When this rocking of the settable lever takes place, the detent lever 91 raises the laterally turned end 151 from the lug 152 from said rack bar of the next higher order due to the tension of spring 96. The upper end of said 115 detent lever at the same time engages over the rear end of the settable lever and holds the same in set position until the cam plate 128 is reciprocated forwardly, and engaging the rollers 126 rocks the carrying levers 117 120 so that the carrying bars 116 are moved rearward. Those carrying bars which have been lowered as thus explained will, during this rearward movement, engage the shoulder 50 of the rack bar 20 of the next higher order, 125 and thereby rotate the type sector and the associated accumulator wheel of said next higher order, one tooth space, so as to add thereto one unit, which thereby effects the carrying. After the carrying has been 130

affected, the accumulator carriage moves rearwardly bringing the lower arm 95 of the detent levers into engagement with the releasing rod 70 whereby the settable levers 87 are released and resume their normal position due to the action of the spring 101. At the same time the cam face 106 of the restoring levers engages the restoring rod 107 and thereby raises the pendant links 110 of the carrying bars 116. When the cam plate 128 again reciprocates rearwardly, the carrying levers are restored to their normal position under the influence of the spring 118. At the same time, the restoring levers 160 fulcrumed on the inner face of the cheek plates 10 are engaged by pins 161 carried on the reciprocating racks 131 and projecting through the slots 163. This engagement causes the restoring rod 164 carried by the lower ends of said levers 160 to engage and restore to normal position any rack bar that has been kicked back during carrying but does not affect the position of the accumulator wheel 34 since it is now 25 out of engagement with the teeth 33.

The total taking mechanism.

During the printing and accumulating of an item, the accumulator is moved forwardly so as to mesh with the teeth 33 on the type sectors during the rearward or return stroke of the rack bars. When a total is taken, the reverse is the case and the accumulator is moved forward during the forward initial stroke of the rack bars and the drive bar 52. This reversal of the cycle of the reciprocation and the mechanism for bringing it about is fully described in said copending application.

When the total taking process is initiated, the stop pins 11 and the abutment levers 40 are in depressed position and it is necessary that the abutment levers be raised in order to clear the fixed zero stop and also to have driving engagement with the drive bar.

For this purpose there is provided a pair of U-levers 170 fulcrumed on the rod 171 carried upon ears 172 stamped from the outer cross plate 14. Between the upper end of the supporting arms 174 of said U-levers is supported the raising rod 175 adapted to engage the lower edge of the abutment levers. This rod may be yieldably raised by means of the springs 176 strained between the hooks 178 on the inner cross plate and hook 179 carried by the lifting arm. The raising rod is held depressed by means of the latch plate 181 having its upper edge pivotally mounted between ears 182 stamped from the upper guide plate 12. The lower edge of the latch plate engages in the shouldered notch 183 in the supporting arm 174. One lower corner of the latch plate is provided with an ear 184 to which is pivotally secured a link 185 having its

forward end connected to a pin 186 passing through a slot 187 in the cheek plate and carried by a vertical lever 188. The lower end of the vertical lever is rounded and engages in a cam slot 189 (Fig. 10) disposed in the active end of the total shift lever. The inner end of the total shift lever is fulcrumed on a pivot post 193 (Fig. 9) mounted upon the base or any suitable fixed part of the machine. Secured below and spaced from the total shift lever is the supporting plate 195 provided with downturned ends 196 and 198, and spaced from the total shift lever by means of spacing posts 200. Between the lever and the supporting plate is secured a spring housing 201 in which is slidably disposed a plunger 203 provided with a plunger head 204 passing through the shift lever and engaging in the shifting groove 206 of the shifting cam 207 mounted on the shaft 208.

The plunger is yieldably moved into said engagement with cam groove 206 by means of a spring 210 disposed in said housing and compressed between the supporting plate 195 and collar 211 carried at the lower end of the plunger head. The plunger is normally held out of engagement by means of an elbow pawl 212 pivotally mounted upon the bracket 213 carried on the supporting plate and provided with an end projection 214 adapted to snap behind the retaining head 215 on the end of the plunger 203 under the influence of a spring 217 strained between said elbow pawl and the downturned arm 198. The downturned arm 196 carries a terminal block 216 on which is secured the outer casing of a flexible connection of the total cables 219 leading from the designation change sensing mechanism and the total card operated total mechanism.

When a total is to be taken, the terminal pin of the inner wires of one of these cables operates the elbow pawl 212 releasing the retaining head 215 whereupon the plunger 110 is thrown into the shifting groove 206. This shifting groove is spiral in form and causes the total shift lever to shift rearwardly, moving the lower end of the vertical lever 188 toward the stop pins, and moving the upper end of the vertical lever in the opposite direction, thus drawing the latch plate 181 out of the notch 183 and permitting the spring 176 to move the raising rod 175 to raise the abutment levers 40 until the shoulders 55 clear the fixed zero stop, and the shoulder 51 gets in front of the drive bar 52, whereby the rack bars are driven forward as shown in Fig. 15.

The rack bars are carried forward by the transverse bar 52 until the radial face 83 of the accumulator wheels engages the rear face of the lower end 89 of the horizontal levers 87. Since all of the accumulator wheels 34 will not revolve the same distance,

and since it is necessary that the bar 52 move to the limit of its forward movement, means are provided for releasing the bar 52 from the shoulders 51 of such rack bars as have reached their limit of movement due to engagement of faces 83 with the ends 89 of levers 87. When this engagement takes place the roller 81 of each accumulator wheel (Fig. 5) engages with a rounded projection 220 (Fig. 6) on a vertically movable bracket 221. The brackets 221 are provided with a lower engaging roller 223 and are pivoted on a transverse rod 224 mounted upon the cheek plates 10 of the machine whereby substantially vertical movement is permitted to the brackets and the rollers carried thereon. When the rounded projection 220 is engaged by the rollers 81 as just explained, the rollers 223 engage and lower the abutment levers 40; hence the rearwardly disposed shoulders 51 of the abutment levers are lowered and permit the transverse bar 52 to pass on forwardly leaving the rack bars as positioned by the abrupt shoulder 83 of the accumulator wheels. After the complete forward movement of drive bar 52 the type 32 on the type sectors 30 are in position for printing. In order to keep the type properly aligned, an aligning bar 260 is provided which engages between teeth 33 of the sector 30 at this time.

The lower part of the bracket 220 is extended to form a spacing piece 227 adapted to engage between the abutment levers and the rack bar of the next higher order to hold them and the brackets properly spaced at this point.

After the rack bars have been positioned as above described, the raising rod 175 is lowered by the engagement of the projections 230, on the supporting arms, by the pin 231 carried on the active end of the restoring lever 232 fulcrumed on the rod 234 and provided at its motive end with a roller 235 engaging in the cam groove 236. This permits the latch plate 181 to be moved back into the notch 183 under the action of the total shift lever 190.

50 *Rack bar holding mechanism.*

Since during the total taking operation, no stop pin 11 is raised, additional provision is made for preventing retrograde movement by the rack bars.

55 Pivoted on the ears 240 (Fig. 2) of the upper plate is a pawl frame 241 comprising end pieces 242 and a comb plate 243 between the teeth of which are disposed pawls 244 mounted on the fulcrum rod 245 carried in said end pieces. The active ends of said pawls are individually yieldably held upward by springs 246 strained between the outer ends of the pawls and the lower part of the comb plate.

60 The pawl frame is normally held with

the pawls out of operative relation with the ratchet teeth 25 of the rack bars, by means of the shorter arm 248 of the U-levers engaging the laterally turned lower finger 249 of the pawl frame; but when the U-levers are released by the latch plate 181, the springs 250, strained between said fingers and a fixed rod 251, move said frame into operative position, in which position the pawls may engage the ratchet teeth 25 as shown in Fig. 15. When the supporting arm 174 is lowered by the rod 231, the pawl frame is moved to inoperative position.

65 *Abutment lever depressing mechanism.*

Before beginning the new operation of registering an item or taking a total, it is necessary to insure that no abutment lever be left raised. To accomplish this there is provided a rod 255 carried between the drive levers 139 and projecting through slots 256 in the cheek plates. This rod, on each forward stroke of the drive levers, engages the cam edge 258, provided by the upwardly projecting lug 259 on the abutment levers, and thereby positively lowers the abutment levers.

70 *The column cut out device.*

Figs. 2 and 8 show the mechanism for holding out of operation a rack bar and associated type sector so that they will not be operated by the drive bar 52 to set up numerals on the type sector.

This mechanism, as shown, comprises a 75 slide-bar 280 slidably received on a side face of the rear extension 281 of the abutment levers. Each slide bar is provided with a pair of guide slots 282 receiving pins 284 projecting from the abutment levers. Said 80 slide bars have their inner ends laterally offset as at 285 to receive the rear end of the rack bar 20 between the off-set portion and the abutment lever. The end of the rack bar is provided with a notch 286 in which 85 engages a locking pin 287 fixed on the inner face of the off-set portion of the slide bar. The slide may be manipulated by means of the pin 288.

When the slide bar is in rearward position, 90 the abutment lever functions normally. When the slide bar is in forward position the abutment lever is held against upward movement into driving engagement with the drive bar 52 or out of engagement with the 95 zero stop.

The various operations have been fully described hereinbefore except the following, which will be readily understood from the foregoing and need now be only briefly 100 summarized as follows:

As the perforated cards are fed through the machine, for each column a pin 11 is either raised or not raised, depending upon the perforation of the column. If the col- 105

umn has a zero perforation then neither a stop pin 11 nor an abutment lever is raised, and the drive bar 52 remains free. If a numeral stop pin is raised, the abutment lever is also raised, the reciprocating transverse bar 52 being in its rear position of movement; and the rearwardly disposed shoulder 51 of the abutment lever 40 is disposed in front of the transverse bar. The transverse bar then moves forwardly until the shoulder 49 of the elbow lever is forced into contact with the rear face of the raised stop pin 11, thus forcing down the abutment bar and the rearwardly facing shoulder 51, permitting the transverse bar 52 to travel free. Any movement of the rack bar which has then taken place is determined by the position of the stop pin then raised, and this movement is communicated to the type sector whereby the type is positioned for printing. As this forward movement of the rack bars takes place the shoulder 57 engages the raised stop pin and prevents any retrograde movement of the rack bars or the type sectors after the transverse bar 52 has been freed. Before the printing takes place the locking and alining bar 260 engages between the teeth 33 and holds the type sectors locked and alined while the printing carriage forces the paper against the type. After the printing takes place the transverse bar 52 commences its rearward movement and before it has engaged the forwardly disposed shoulder 50, the locking and alining bar 260 is moved out of contact with the teeth 33, the stop pins 11 are lowered, and the rack bars are retracted by the transverse bar 52 engaging the shoulder 50.

When a total is taken the pins 11 are not raised, but the latch plate 181 is retracted and the raising rod 175 raises the abutment levers. At the beginning of the forward movement of the transverse bar 52, the abutment levers 40 are held raised by means of the spring 176 until the accumulator wheels which are all then in mesh with the type sectors, turn in anti-clockwise direction until the abrupt shoulder 83 of the accumulator wheels engages the lower end 89 of the horizontal lever. At this instant, the projecting roller 81 engages the projection 220, and the roller 223 depresses the abutment levers and permits the transverse bar 52 to pass on free. At the same time the pawls 244 move to operative position and prevent retrograde movement of the rack bars.

I claim:

1. In an apparatus of the character described, the combination of movable members; a drive member for the movable members; normally inoperative means for preventing retrograde movement of the movable members; means for yieldably moving said preventing means into operative relation with the movable members when a total

is to be taken; and an accumulating mechanism operatively associated with said movable members and adapted, at the end of their total taking movement, to disconnect them from the drive member.

2. In an apparatus of the character described, the combination of movable members; a drive member; means for preventing retrograde movement of the movable members; means for moving said movable members into driving relation with the drive member and the preventing means into operative relation with the movable members when a total is to be taken; and an accumulating mechanism operatively associated with said movable members and adapted to disconnect them from the drive member.

3. In an apparatus of the character described, the combination of movable members; a drive member; normally inoperative means for preventing retrograde movement of the movable members; means for yieldably moving said movable members into operative relation with the drive member when a total is to be taken and for moving the preventing means into operative relation with the movable members; and an accumulating mechanism operatively associated with said movable members and adapted, to disconnect them from the drive member.

4. In an apparatus of the character described, the combination of movable members; a drive member adapted to drive the movable members; an accumulating mechanism operatively associated with movable members and adapted to move the movable members from operative relation with the drive member; a frame; means carried on said frame for preventing retrograde movement by the movable members; and means actuated, when a total is to be taken, to operatively connect the drive member with the movable members and to move said frame to position to prevent retrograde movement of said movable members.

5. In an apparatus of the character described, the combination of actuating bars; an abutment member carried on each bar; a drive member adapted to drive raised abutment members; an accumulating mechanism associated with said bars and adapted to depress the abutment members; a frame; pawls carried in said frame; a lever normally adapted to hold said frame away from movement toward said bars and tending to raise said abutment members; a latch adapted to hold the lever against raising the abutment members; and means for actuating said latch when a total is to be taken to permit said lever to raise said abutments and move said pawls into engagement with said bars.

6. In an apparatus of the character described, the combination of actuating bars

70

provided with ratchet teeth; an abutment member pivoted to each bar; a drive bar adapted to drive raised abutment members; accumulator mechanism associated with said bars and, when in total taking position, adapted to depress the abutment members; a pawl frame yieldably pressed toward said teeth; pawls carried on said frame; a lever normally adapted to hold said frame away from movement toward said teeth and provided with a notch; a raising rod carried by the lever; springs tending to cause said lever to raise said rod; a pivoted latch plate adapted to engage in said notch and hold the rod depressed; and a total lever for disengaging said latch plate from said notch to permit said members to raise said rod and abutment lever and to permit said frame to move the pawls into engagement with the ratchet teeth.

7. In an apparatus of the character described, the combination of type sectors; rack bars cooperating with the type sectors and provided with ratchet teeth; an abutment lever pivoted to each rack bar and provided with an outwardly disposed shoulder; a drive bar adapted for driving engagement with said shoulders; accumulators associated with said sectors and each provided with a projection; means for stopping the accumulators at the end of their total taking movement; a bracket associated with each abutment lever and adapted to be engaged by said projection when in total taking position to depress the abutment lever; a pivoted pawl frame; yieldable pawls carried in said frame; a spring tending to move said frame toward said ratchet teeth; a pair of U-levers each normally adapted to hold said frame away from movement toward said teeth and provided with a notch; a raising rod carried by the lever; springs tending to cause said lever to raise said rod; a pivoted latch plate adapted to engage in said notch and hold the rod depressed; and a total lever for disengaging said latch plate from said notch to permit said U-levers to raise the said rod and abutment levers and to permit said frame to move the pawls into engagement with the ratchet teeth.

8. In an apparatus of the character described, the combination of type sectors; rack bars cooperating with the type sectors and each comprising an inwardly turned shoulder and ratchet teeth; an abutment lever pivoted to each rack bar and provided with an outwardly disposed shoulder; a reciprocating drive bar adapted to be disposed between said shoulders; an accumulating mechanism associated with said type sectors and comprising accumulator gears each provided with a roller projection; means for stopping the gears at the end of

their total taking movement; a roller bracket associated with each abutment lever and adapted to be engaged by said roller projection and each carrying a depressing roller adapted when in total taking position to press the abutment lever; a pivoted pawl carrying frame; yieldable pawls carried in said frame; a spring tending to move said frame toward said ratchet teeth; a pair of U-levers each normally adapted to hold said frame away from movement toward said teeth and provided with a notch; a raising rod carried at the upper end of the supporting arms; springs tending to raise said supporting arms; a pivoted latch plate adapted to engage in said notches and hold the arms depressed; and a total lever for disengaging said latch plate from said notches to permit said U-levers to raise said rod and abutment levers and to permit said frame to move the pawls into engagement with the ratchet teeth.

9. In an apparatus of the character described, the combination of abutment members adapted when actuated to bring about accumulation; a drive member; a zero stop; and settable stops adapted at selected positions to move the abutment members out of engagement with the zero stops and into engagement with the drive member and for stopping the abutment members.

10. In an apparatus of the character described, the combination of accounting mechanism comprising abutment members adapted when actuated to bring about accumulation; a drive member; settable stops adapted to move the abutment members into engagement with the drive member; and means associated with each abutment member and adapted to engage a set stop to stop the abutment lever and move it out of engagement with the drive member into engagement with the set stop.

11. In an apparatus of the character described, the combination of accounting mechanism comprising abutment members adapted when actuated to bring about accumulation; a drive member; a zero stop; settable members adapted to move the abutment member out of engagement with the zero stop and into engagement with the drive member; and means associated with each abutment member and adapted to engage a set settable member to stop the abutment member and move it out of engagement with the drive member into engagement with said set settable member.

12. In an apparatus of the character described, the combination of a plurality of actuating bars adapted when actuated to bring about accumulation; an abutment lever fulcrumed to each bar; a device loosely engaging each actuating bar and abutment lever; a drive bar adapted to have driving

relation with the abutment lever; and rows of selective stops adapted to move the abutment levers to engage the drive bar and to be engaged by said devices to lower the 5 abutment levers until said abutment levers engages the selective stops and the levers clears the drive bar.

13. In an apparatus of the character described, the combination of a plurality of 10 actuating bars; an abutment lever movably secured to each bar; a device loosely engaging each rack bar and abutment lever; a drive bar adapted to have driving relation with the abutment lever; a zero stop engaged by said abutment lever to hold the actuating bar against registering movement; and rows of selective stops adapted to move the abutment levers into engagement with the drive bar and to disconnect the abutment levers from the zero stops and to cause 20 said devices to move the abutment levers into engagement with said selective stops and out of engagement with the drive bar.

14. In an apparatus of the character described, the combination of a plurality of 25 actuating bars; an abutment lever fulcrumed to each bar and provided with an outwardly facing abutment and an inwardly disposed lower shoulder; a device loosely 30 engaging each rack bar and abutment lever; a drive bar adapted to have driving relation with the abutment lever when the latter is raised; a zero stop adapted to engage said inwardly facing shoulder and hold the actuating bar; and a row of selective stops 35 adapted to lift the abutment lever into engagement with the drive bar and to clear the zero stop and to engage said device to lower the abutment lever until said abutment 40 engages said selective stop and the lever clears the drive bar.

15. In an apparatus of the character described, the combination of a plurality of 45 actuating bars; selective means controlled thereby; an abutment lever fulcrumed to each bar and provided with an outwardly disposed upper shoulder, an outwardly facing lower inclined abutment and an inwardly disposed lower shoulder; an elbow device 50 pivotally mounted on each rack bar and engaging the abutment lever; a transverse reciprocating drive bar adapted to be disposed behind said outwardly disposed upper shoulder; a fixed zero stop adapted to engage said inwardly facing shoulder and hold the actuating bar against forward 55 movement; and vertically movable stops disposed under each abutment lever and adapted to lift the abutment lever to clear the zero stop, the raised stop being adapted 60 to be engaged by said device to lower the abutment lever until said inclined abutment engages said stop and the outwardly facing upper shoulder clears the drive bar.

16. In an apparatus of the character de-

scribed, the combination of a plurality of actuating bars each having an inwardly disposed upper shoulder; an abutment lever fulcrumed to each bar and provided with an outwardly disposed upper shoulder, an 70 outwardly facing lower inclined abutment and a downward projection forming an inwardly disposed lower shoulder and an outwardly and downwardly facing cam edge, said upper shoulder being adapted to be 75 spaced from and opposed to said inwardly disposed upper shoulder; an elbow device pivotally mounted on each actuating bar and loosely engaging the abutment lever and provided with a downwardly extending 80 arm; a transverse reciprocating drive bar adapted to be disposed between said upper shoulders when the abutment lever is raised; a fixed zero stop over which said edge is adapted to cam, said stop being adapted to 85 engage said inwardly disposed lower shoulder and hold the actuating bar in zero position; and vertically movable stops disposed in a row under each abutment lever and adapted to lift the abutment lever to clear 90 the zero stop and adapted to be engaged by said arm to lower the abutment lever until said inclined abutment engages said stop and the outwardly facing upper shoulder 95 clears the drive bar.

17. In an apparatus of the character described, the combination of movable members; a drive member for driving the movable members; an accumulator associated with each bar and carrying a roller adapted, when the accumulator is in total taking 100 position, to move the movable member out of operative relation with the drive member.

18. In an apparatus of the character described, the combination of movable members; a drive member for reciprocating the movable members; an accumulator operatively associated with each movable member and provided with a roller projection; 110 and a bracket associated with each movable member and adapted to be engaged by said roller projection when the accumulator is in total taking position and adapted when thus engaged to move the abutment member 115 out of operative relation with the drive member.

19. In an apparatus of the character described, the combination of actuating bars; an abutment member carried on each bar; 120 a drive member adapted to engage the abutment members for reciprocating said bars; an accumulator associated with each bar and provided with a roller projection; means for stopping the accumulator in total taking position; and a bracket associated with each abutment member and adapted to be engaged by said roller projection when the accumulator is in total taking position and adapted when thus engaged to move the 125 130

abutment member out of operative relation with the drive member.

20. In an apparatus of the character described, the combination of actuating bars; an abutment member carried by each bar; a drive bar for reciprocating the bars when said members are raised; accumulators associated with each bar and each provided with a roller; means for stopping the accumulators in total taking position; a pivoted member associated with each abutment member and adapted to be engaged by said roller when the accumulator is in total taking position; and a depressing roller carried on each bracket and adapted when said bracket is thus engaged to depress the abutment member to permit it to clear the drive bar.

21. In an apparatus of the character described, the combination of actuating bars; an abutment member carried by each bar and provided with an outwardly disposed shoulder; a drive bar adapted to engage said shoulders for reciprocating the bars; accumulator gears operatively associated with said bars and each provided with a roller; means for stopping the gears in total taking position; a pivoted roller bracket associated with each abutment member and provided with a roller-engaging projection adapted to be engaged by said roller when the gear is in total taking position; and a depressing roller carried on each bracket and adapted when said projection is thus engaged to press the abutment lever to permit said outwardly disposed shoulder to clear the drive bar.

22. In an apparatus of the character described, the combination of an adding mechanism comprising type sectors and rack bars cooperating with the type sectors, each rack bar having an inwardly turned shoulder; an abutment lever pivoted to each rack bar and provided with an outwardly disposed shoulder; a transverse drive bar adapted to be disposed between said shoulders for reciprocating the rack bars; an accumulating mechanism associated with said type sectors and comprising accumulator gears; a collar secured to each gear and provided with a zero position stop, a roller projection on each gear; means adapted to engage said stops for stopping the gears in total taking position; a vertically movable pivoted roller bracket associated with each abutment lever and provided with a roller-engaging projection adapted to be engaged by said roller projection when the collar is in total taking position; and a depressing roller carried on each roller bracket and adapted when said projection is thus engaged to press the abutment lever to permit said outwardly disposed shoulder of the abutment lever to clear the transverse drive bar.

23. In an apparatus of the character described, the combination of actuating mem-

bers; an abutment member carried on each actuating member; a drive member; means for moving said abutment members into driving engagement with said drive member; and means for locking said abutment members to the actuating members out of driving relation with the drive member.

24. In an apparatus of the character described, the combination of a fixed zero stop; an accumulator; abutment members operatively associated with the accumulators; a drive member; means for moving said abutment members into driving engagement with said drive member; and means for locking said abutment members in inoperative relation with the drive member and in engagement with the zero stop.

25. In an apparatus of the character described, the combination of actuating members; a fixed zero stop; an abutment member carried on each actuating member; a drive member; means for moving said abutment members into driving engagement with said drive member; and means for locking said abutment members to the actuating members in inoperative relation with the drive member and in position to engage the zero stop to prevent registering movement.

26. In an apparatus of the character described, the combination of an accounting mechanism comprising actuating bars; a zero stop; an abutment lever pivoted to each actuating bar, an inwardly disposed shoulder on said abutment lever adapted to engage said zero stop; a drive bar; means for moving said abutment levers into driving engagement with said bar; and means for locking said abutment levers to the actuating bar in engagement with the zero stop and out of engagement with the drive bar.

27. In an apparatus of the character described, the combination of accounting mechanism comprising actuating bars each provided with a notch; a zero stop; an abutment lever pivoted to each actuating bar and adapted to engage said zero stop when the lever is lowered; a drive bar; means for moving said abutment levers upwardly into engagement with said drive bar; a pair of guide pins projecting laterally from each of said levers; slide bars each provided with a pair of slots adapted to receive said pins; and a locking pin on each slide bar and adapted to enter said notch when the slide bar is moved inwardly.

28. In an apparatus of the character described, the combination of an adding mechanism comprising actuating bars each provided with a notch in its rear end; a fixed zero stop; an abutment lever pivoted to each actuating bar and provided with a rear extension and an inwardly disposed shoulder adapted to engage behind said zero stop when the lever is lowered; a transverse drive

bar; means for pressing said abutment levers upwardly into driving engagement with said drive bar; an accumulating mechanism operatively connected to said actuating bars; a pair of guides projecting laterally from said rear extension; column cut-out slide bars slidably received on the sides of said rear extensions and provided with a pair of slots adapted to receive said guides, 10 said slides having their inner ends laterally off-set to receive the notched rear end of the actuating bar between the off-set end and said extension; and a locking pin projecting from the inner face of said off-set end and adapted to enter the notch when the slide bar is moved inwardly.

29. In an apparatus of the character described, the combination of actuating bars; an accounting machine controlled by the 20 actuating bars; an abutment lever pivotally secured on each actuating bar; a drive member; means adapted to raise said abutment levers into driving relation with the drive member; means for lowering the levers in accordance with the number to be registered; a reciprocating carrying means; and means carried by the reciprocating carrying means for depressing said abutment levers.

30. In an apparatus of the character described, the combination of actuating bars; an accounting machine controlled by the actuating bars and comprising a reciprocating carrying part; an abutment lever pivotally secured on each actuating bar and provided with an outwardly disposed shoulder; a transverse drive bar adapted to be disposed behind said shoulders; means adapted to raise said abutment levers; means for lowering the levers in accordance with the number to be registered; means for reciprocating said carrying part; and means carried by the reciprocating means for depressing said abutment levers.

31. In an apparatus of the character described, the combination of rows of movable stops; an actuating bar associated with each row of stops and provided with an inwardly disposed shoulder; an accounting machine controlled by the actuating bars and comprising a reciprocating carrying cam plate; an abutment lever pivotally secured on each actuating bar adapted to be lowered by any raised stop and provided with an upwardly and outwardly facing cam edge and with an outwardly disposed shoulder; a transverse drive bar adapted to be disposed between said shoulders; means for reciprocating said cam plate inwardly to effect carrying and comprising drive levers; means for reciprocating the drive levers; and a rod secured on said drive levers and adapted to engage said cam edge.

32. In an apparatus of the character described, the combination of actuating bars; an accounting machine controlled by the ac-

tuating bars and comprising a reciprocating carrying plate; an abutment lever pivotally secured on each actuating bar and provided at its rear part with an upwardly and outwardly facing cam edge and at its intermediate part with an outwardly disposed shoulder; means for raising and lowering said abutment levers in accordance with the number to be accumulated; a transverse drive bar adapted to be disposed behind said shoulders; a reciprocating rack secured to each side of said carrying plate; spindles passing through the cheek plates below said racks; pinions thereon meshing with the racks; a fixed rack secured to each cheek plate and meshing with said pinions; levers for reciprocating the plate; and means on each drive levers adapted to engage said cam edge to depress the abutment lever.

33. In an apparatus of the character described, the combination of a pair of cheek plates; rows of movable stops disposed between said cheek plates; means for actuating the stops; an actuating bar associated with each row of stops and provided with an inwardly disposed shoulder; an accounting machine controlled by the actuating bars and comprising a reciprocating carrying cam plate; an abutment lever pivotally secured on each actuating bar and provided at its rear part with an upwardly and outwardly facing cam edge and at its intermediate part with an outwardly disposed shoulder, said lever being adapted to be lowered by any raised stop; a transverse drive bar adapted to be disposed between said shoulders; a reciprocating rack secured to each side of said cam plate; spindles passing through the cheek plates below said racks; pinions thereon meshing with the racks; a fixed rack secured to each cheek plate and meshing with said pinions; a spindle drive lever fulcrumed to each cheek plate and provided with a slot receiving said spindle; means for reciprocating the drive levers; and a rod on said drive levers and adapted to engage said cam edge.

34. In an apparatus of the character described, the combination of a fixed zero stop; movable members; a register controlled by the members; drive means for the movable members; means for anchoring said movable members to the zero stop, and a row of set-up devices each of which when set up bears against and dislodges said anchoring means from said zero stop.

35. In an apparatus of the character described, the combination of a fixed zero stop; movable members; a register controlled by the members; drive means for the movable members adapted to be connected thereto; movable means carried by the movable members for locking said movable members in anchoring relation with the zero stop, and set-up means for dislodging said movable

locking means from said zero stop and for connecting it to said drive means.

36. In an apparatus of the character described, the combination of a zero stop; movable members; a register controlled by the members; drive means for the movable members; movable means carried by the movable members and movable relative to the movable members into and out of anchoring relation with the zero stop for anchoring the movable members to the zero stop; and means for positioning the movable members

and directly bearing against and actuating the movable means out of said anchoring relation.

15

37. In an apparatus of the character described, the combination of a fixed zero stop; movable members; a register controlled by the members; drive means; and movable means for anchoring said movable members to the zero stop or to the drive means.

WILLIAM W. LASKER.

CERTIFICATE OF CORRECTION.

Patent No. 1,705,982.

Granted March 19, 1929, to

WILLIAM W. LASKER.

It is hereby certified that error appears in the printed specification of the above numbered patent requiring correction as follows: Page 3, line 20, for the misspelled word "whereup" read "whereupon"; page 5, line 85, for "grove" read "groove"; page 11, line 83, claim 32, for the word "each" read "said"; and that the said Letters Patent should be read with these corrections therein that the same may conform to the record of the case in the Patent Office.

Signed and sealed this 30th day of July, A. D. 1929.

(Seal)

**M. J. Moore,
Acting Commissioner of Patents.**
